UNITED STATES PATENT OFFICE.

HARRY T. EDWARDS, OF SAN FRANCISCO, CALIFORNIA, ASSIGNOR OF ONE-HALF TO RUSSELL BERKENKAMP, OF SAN FRANCISCO, CALIFORNIA, TRADING UNDER THE NAME OF AJAX FOUNDRY COMPANY.

CASTING-CORE.

1,384,438.

Specification of Letters Patent. Patented July 12, 1921.

Continuation of application No. 320,252, filed August 27, 1919. This application filed August 4, 1920. Serial No. 401,157.

To all whom it may concern:

Be it known that I, HARRY T. EDWARDS, a citizen of the United States, residing at San Francisco, in the county of San Francisco and State of California, have invented 5 certain new and useful Improvements in Casting-Cores, of which the following is a specification.

This application is a continuation of my 10 allowed application Serial No. 320,252, filed August 27, 1919.

This invention relates to a casting core. In foundry practice it has been a problem to properly anchor the cores of large castings, especially when the center of gravity or body of the casting is disposed when cast, at one side of the vertical, and eccentric to its supporting surfaces, as in the production of pipe elbows and other castings 20 formed on the arc of a circle. In most instances the cores for these molds have been made with elaborate core arbors and chaplets. When the casting has been made, it has, of course, embodied the chaplets in its 25 wall, and in many industries, this piece of metal has weakened the wall, and often resulted disastrously. It is the principal object of the present invention, therefore, to provide a casting core, which may be utilized 30 in forming castings normally requiring anchors for their support in the mold, and which casting will be free of metal plugs in their walls and when desired will be of substantially uniform thickness 35 throughout.

In its preferred form the present invention contemplates the use of a casting core, the opposite ends of which are formed with downwardly converging sides and a flat 40 horizontal surface coinciding with the dividing line between the cope and drag of the flask, and which surface will receive the sand of the cope and hold the core rigidly without the use of other anchorage, but the invention is not limited to these preferred 45 features.

Such preferred embodiment of the invention is illustrated by way of example in the accompanying drawings, in which—

50 Figure 1 is a view in end elevation showing the formation of a circular core, and the shape of the core print at the end thereof.

Fig. 2 is a view in plan showing the drag portion of a flask and illustrating the shape

of the core used in connection with a pipe elbow mold.

Fig. 3 is an enlarged view in vertical section taken centrally of an arcuate mold and more clearly showing the manner in which the core is anchored by the combined action 60 of the cope and drag.

Referring more particularly to the drawings, 10 indicates the drag portion of a flask and 11 indicates its cope, these portions being used to form a mold for a casting 65

which is not symmetrical in its design but lies eccentric to its central axis and requires that the core 12, therefore, shall be properly supported in order to prevent its falling and thereby causing a variation in the thickness of the walls of the casting. The core in the present instance is shown as having a body portion of circular cross-section and being fitted at its opposite ends with extensions 13. These extensions have horizontal flat faces 14 which agree with the horizontal equator of the section, as shown in Fig. 1. At the opposite ends of this plane surface 14, downwardly converging side planes 15 and 16 are formed. In the present instance, the side planes would represent the hexagonal face of a circle equal to the diameter of the core. The faces 15 and 16 70

may be united by a flat face 17 of equal dimensions and which stands parallel to the upper equatorial plane 14. In some instances, this last named face 17 may be eliminated and the lower contour of the core continued to the end of the extension 13. It is 75

common practice to form the extensions of the cores represented by core print for a considerable distance at the ends of the pattern, and this requires that large and heavy cores must be made which in turn will necessitate the use of large flasks. Attention is particularly directed to the fact that in the present instance and by forming the core print, as shown in the drawing, a very short core print is necessary with the result that for ordinary work the cores may be 80 made on the bench and when used in a mold will permit a mold of considerably smaller dimensions to be used than would otherwise be possible.

In the practice illustrated in the drawings, 105 a pattern is used having a core print of the formation shown in Fig. 1 on its lower half. The upper half of the pattern will merely

represent the mold of the article to be made. After the cope and drag of the mold have been properly formed the core may be placed in position with the extensions 13 in the 5 recessed portions of the drag as indicated by the numeral 18 in Fig. 3. It will be understood that these recesses will agree in sectional formation with the extensions 13 and will thus provide opposite inclined 10 faces which will coincide with the faces 15 and 16 of the core while insuring that the equatorial face 14 will lie directly along the dividing line between the cope and the drag. The cope is then placed in position 15 and will rest upon the drag and the core in the manner clearly shown in Fig. 3. It will thus be seen that the sand in the cope will act to hold the core print in position and will prevent rotation of the print due to the 20 fact that the pressure upon the plane 14 will hold the faces 15 and 16 within the recess 18 and as these faces coincide with the faces of the mold made by the core print it will be impossible for the core to turn. This will 25 insure that the cope will act to hold the core in a non-rotating and wedged position and will provide uniformity in the thickness of the upper and lower walls of the finished casting. After the casting has been poured 30 it may be removed from the flask and the core very easily cleaned therefrom. An examination of the walls of the casting will thereafter prove that substantial uniformity in thickness has been maintained through- 35 out the top and bottom of the structure and furthermore, that the walls will be of uniform strength, due to the fact that no chal-lets or anchors have been passed through the side walls.

40 It will thus be seen that by use of a core formed as previously described, the sand of the cope and drag will act to hold the core in position without the use of anchors, chal-lets or other supports and that irrespective 45 of the unbalanced weight of the core, a casting may be made having walls of uniform thickness, the operation being performed with less material than is usually required and within flasks of smaller dimensions.

50 While I have described the preferred form of my invention, it will be understood that various changes in the combination, construction and arrangement of parts might be made by those skilled in the art, without departing from the spirit of the invention, 55 as claimed. For example, while the preferred and apparently simpler form of my invention involves an arrangement whereby the flat upper surfaces on the core exten- 60 sions coincide with the dividing line between the drag and cope, it is obvious that the movement and rotation of the core can be prevented by the coengagement of the non-circular extensions with the molding sand 65 of the drag and cope regardless of whether

the extensions are provided with flat surfaces which are flush with the dividing line. Conceivably also the relations between the drag and the cope might be reversed from those shown in the drawing and hereinbefore described. I, therefore, contemplate such variations which embody my invention as set forth in any of the claims.

I claim:

1. A casting core having core prints by 75 which it is designed to be held immovable and non-rotatable, by the sand of the cope and drag portions of a mold.

2. A casting core of unbalanced weight, 80 and core prints formed thereupon and against which the sand of the cope of a mold may act to prevent rotation thereof.

3. A casting core, the weight of which is eccentric to the point of its support, said core being formed with extending prints 85 at its opposite ends having downwardly ex- tending flat sides inclosed within the sand of the drag portion of the mold, and a flat face in alignment with the parting line of the cope and drag and upon which the sand 90 of the cope is adapted to rest to hold the core against movement.

4. A casting core comprising a core body, 95 the weight of which is eccentric to its point of support and hexagonal extending prints formed at the ends of said core with their upper faces representing horizontal planes occurring along the dividing line of the cope and drag and upon which the sand of the cope may rest to hold the prints in their 100 seated positions.

5. A method of casting, one step of which is to anchor the casting core by the binding action of the cope and drag portions of a mold, upon the core prints at the ends 105 thereof.

6. A method of anchoring a casting core, 110 which core is of unbalanced weight in relation to a horizontal line extending through its end points of support, said line agreeing with the line of separation of the cope and drag of a mold, which method consists in forming the portion of the core within the drag portion of the mold with prints having flat upper faces agreeing with the parting 115 line and inclined side faces adapted to rest against the sand and prevent rotation of the core when the cope rests upon the upper flat faces of said prints.

7. A method of casting pipe elbows and 120 the like which consists in providing a cylindrical core for the mold of said pipe, said core being formed with end prints extending only within the drag portion of a mold and having flat upper faces lying along the 125 parting line of the mold and inclined side faces resting against the sand of the drag whereby the combined action of the three faces when the cope is in position will prevent rotation or displacement of the core. 130

8. A core to be used in casting pipe elbows and the like, comprising a body portion of a cross section agreeing with the interior of the casting to be made and adapted to lie with its longitudinal center along the parting line of the mold and end core prints extending from the ends of the body of the core and having an upper face along the parting line of the mold and side faces converging from the opposite edges of said upper face irrespective of the sectional formation of the core and for the purpose of holding the core against movement or rotation when the sand of the cope rests upon the upper faces of the prints. 60
- 5 9. A casting core in which the center of gravity lies at one side of its base of support when in the mold, provided with supporting extensions of non-circular cross-section adapted to seat in corresponding recesses in a mold for holding said core against movement and rotation. 70
- 10 10. A casting core, which is unbalanced relative to its points of support in the mold, provided with supporting projections polygonal in cross-section extending from its extremities. 80
- 15 11. A casting core which is unbalanced relative to its points of support in the mold, provided with supporting projections having flat surfaces and polygonal in cross-section, extending from its extremities, the said projections arranged so that the flat surfaces thereof are adapted to lie in said mold flush with the parting surface between the cope and drag portions of the mold. 85
- 20 12. A casting core which is unbalanced relative to its points of support in the mold, provided with supporting projections extending from its extremities, having flat surfaces polygonal in cross-section, said projections adapted to be anchored between the cope and drag portions of a mold to prevent rotation of the core. 90
- 25 13. A casting core which is unbalanced relative to its points of support in the mold, provided with supporting projections extending from its extremities, having flat surfaces polygonal in cross-section, and converging sides. 95
- 30 14. The combination with the cope and drag portions of a mold, of a casting core in which the center of gravity lies outside of the points of support of said core in the mold, said core being provided at its extremity with supporting projections of non-circular cross section and seated in corre- 100
- 35 spondingly shaped recesses in said mold and held against rotation by the coöperation of said cope and drag. 105
- 40 15. The combination with a mold for molding pipe elbows or the like, of a core for said mold provided with supporting projections at the extremities thereof having flat surfaces thereon, said projections being seated in correspondingly shaped recesses in said mold, with said flat surfaces corresponding with the parting surface between the cope and the drag, said cope and drag portions adapted to anchor said projections in said mold to prevent the rotation of said core. 110
- 45 16. The method of anchoring an unbalanced casting core in a mold which comprises forming supporting projections of non-circular cross section on said core, positioning said core in the mold with the projections in correspondingly shaped recesses in the mold and anchoring the same in position by the pressure between the cope and the drag. 115
- 50 17. The method of anchoring an unbalanced casting core in a mold which comprises forming supporting projections of non-circular cross section of said core having flat surfaces, positioning said core in the mold with the projections in correspondingly shaped recesses in the mold with the flat surfaces flush with the parting surface between the cope and the drag and anchoring the core in position by the pressure between the cope and the drag. 120
- 55 18. A casting core having supporting extensions of non-circular cross-section adapted to seat within correspondingly shaped recesses in a mold whereby the core may be held against movement and rotation. 125
- 60 19. A casting core provided with supporting projections at its extremities of a polygonal cross-section and adapted to be seated in correspondingly shaped recesses in a mold and to be held against rotation by the pressure between the cope and drag portions of the mold. 130
- 65 20. A casting core provided with supporting projections at its extremity having flat surfaces and adapted to be seated in correspondingly shaped recesses in a mold with the flat surfaces flush with the parting surface between the cope and drag portions of the mold and to be held against rotation by the pressure between the cope and drag portions of the mold. 135
